WELL TUBING PLUG

Herbert C. Otis, Shreveport, La.

Application April 13, 1932; Serial No. 605,050

10 Claims. (Cl. 166—13)

This invention relates to a plug for well tubings, and more particularly to an apparatus for use in plugging the tubing of wells while running the same into the well against the flowing pressures existing therein.

An important object of the invention is the provision of a device of this character which, after the tubing has been fully installed, may be opened from the upper end of the well tubing and without depending upon the introduction to the well of any material which might subsequently interfere with operation thereof.

A still further object of the invention is the production of an apparatus of this character which, after having been opened, may be readily closed at any time in order that flow through the tubing may be discontinued or the pressures generated in the well employed to assist in elevating the tubing during removal thereof.

A still further object of the invention is the provision in apparatus of this character of a construction such that the plug, when moved to its inoperative position, in no manner interferes with normal operation of the well.

These and other objects I attain by the construction shown in the accompanying drawings, wherein, for the purpose of illustration, I have shown a preferred embodiment of my invention and wherein:

Fig. 1 is a side elevation partially in section illustrating the first step in installation of tubing employing a plug constructed in accordance with my invention;

Fig. 2 is an enlarged detail sectional view showing the manner in which the plug is held against its seat;

Fig. 3 is an enlarged detail sectional view showing the complete installation and also illustrating the mounting of a fishing tool control and packer for use in reseating the plug; and

Fig. 4 is an enlarged sectional view showing a suitable fishing tool.

Referring now more particularly to the drawings, the numeral 10 designates a well casing and 11 an interiorly disposed tubing, which tubing, as is usual, is sealed to the casing at its upper end and is provided at its lower end with a screen 12 closed at its lower end by a bull plug 13. In accordance with my invention, the upper end of the screen 12 is connected with the tubing 11 through a restricted nipple 14, the lower end of which is formed with a downwardly facing tapering seat 15. For co-action with this seat I provide a plug 16 which may be formed of any suitable material having an up-

wardly facing tapering shoulder 17 so that the plug constitutes a valve for co-action with the tapering seat. The upper end of the plug has embedded therein a pin 18 projecting above the upper end of the plug, the purpose of which will presently appear. Bull plug 13 and the coupling 19 connecting the bull plug to the screen are preferably provided with perforations 20, the purpose of which will presently appear.

In installing the tubing employing plugging means of the type described, the plug is loosely held against the seat in any suitable manner as suggested in Figs. 1 and 2, while tubing is run in the upper end of the casing to and slightly below a point where the casing may be sealed thereto. In Fig. 1, I have shown the upper end of the casing as provided with upper and lower ram gates 21 and 22 and the tubing as having been inserted so that it extends through the upper ram gate which is in sealing engagement therewith.

It will be obvious that at this time the pressure within the well will build up against the plug 16 holding the same in sealing engagement with the seat of nipple 14 so that the holding means C provided for the plug during installation of the tubing to this extent may now be released. The tubing is then run to the desired depth, the well pressure maintaining the plug against its seat, after which the tubing may be sealed to the casing in the usual manner generally illustrated in Fig. 3. To unseat the plug I preferably provide a connection 23 between the well casing 10 and the tubing 11 so that the casing pressure may be introduced to the tubing above plug 16. When the pressure within the tubing equals that within the casing it will be obvious that the plug will still remain seated, for the exposed area of the plug within the tubing is less than that subjected to casing pressures. In order to obtain the relative increase in pressure necessary to unseating of the plug, the casing valves may be opened to reduce the pressure within the casing, or prior to introduction of casing pressures a suitable column of fluid may be introduced to the tubing as through valve 24 so that when casing pressures are introduced to the tubing the pressure upon the upper surface of the plug will overbalance that against the lower surface thereof and cause the same to be unseated. The plug when unseated drops into the bull plug where it is maintained in a vertical position with the pin 18 accessible, open-

ings 20 serving to prevent collection of sand,

or other foreign substances which would interfere with engagement of this pin, by a suitable fishing tool.

If at any time it becomes desirable to again plug the tubing, it is simply necessary that a fishing tool be run into the well through one of the conventional fishing tool fitting apparatuses such as indicated at 25 and be employed to lift the plug until it engages the seat. The tool should be of the friction type so that a release may be effected when the plug has been seated. One suitable for use in this connection is sectionally illustrated in Fig. 4, wherein 26 indicates the body of the tool having a bore 27 for the reception of pin 18, said bore having its lower end formed with a guiding mouth 28 and having in one wall thereof an opening 29 in which is mounted a heavy leaf spring 30 to engage the pin and force it into frictional engagement with the wall of bore 27. As indicated, the wall of the bore may be roughened, as for example by threading, so that the frictional grip between the pin and the tool will be increased. This illustration is purely arbitrary as, obviously, there are numbers of fishing tools which might be employed in this capacity.

Since the construction illustrated is capable of considerable modification without any departure from the spirit of my invention, I do not wish to be understood as limiting myself thereto except as hereinafter claimed.

I claim:

1. The combination with well tubing and a screen, of means connecting the screen and the lower end of the tubing including a downwardly facing valve seat, a valve plug engaging said seat, said plug being freely movable from said valve seat to a position below the screen.
2. The combination with well tubing and a screen, of means connecting the screen and the lower end of the tubing including a downwardly facing valve seat, a valve plug engaging said seat, said plug being freely movable from said valve seat to a position below the screen, and means at the lower end of the screen receiving said plug when separated from its seat.
3. The combination with well tubing and a screen, of means connecting the screen and the lower end of the tubing including a downwardly facing valve seat, a valve plug engaging said seat, said plug being freely movable from said valve seat to a position below the screen, means at the lower end of the screen receiving said plug when separated from its seat, and means on the upper end of the plug for engagement with a fishing tool by which the plug may be returned to its seat.
4. The combination with a tubing having a screen at the lower end thereof, of an inert means sealing the lower end of the tubing, said means being freely displaceable from the lower end of the tubing by pressures generated within the tubing, and being freely movable from the

lower end of the tubing to a point below the screen.

5. The combination with well tubing and a screen, of means connecting the screen and the lower end of the tubing including a downwardly facing valve seat, a valve plug engaging said seat, said plug being freely movable from said valve seat to a point below the screen, and means on the upper end of the plug for engagement with a fishing tool by which the plug may be returned to its seat.

6. The combination with a well tubing having a screen at its lower end, of means providing a downwardly facing valve seat at the interior of the tubing immediately above the screen, a valve plug engaging said seat, said plug being adapted to move from the seat by gravity and to be held in engagement therewith by pressures exterior to the tubing, and means at the upper end of the plug for engagement with a fishing tool by which the plug may be returned to its seat.

7. The combination with a well tubing having a screen at its lower end, of means providing a downwardly facing valve seat at the interior of the tubing immediately above the screen, a valve plug engaging said seat, said plug being adapted to move from the seat by gravity and to be held in engagement therewith by pressures exterior to the tubing, and means in spaced relation to said seat and beneath said screen to receive and support the plug when separated from its seat.

8. The combination with a well tubing having a screen at its lower end, of means providing a downwardly facing valve seat at the interior of the tubing immediately above the screen, a valve plug engaging said seat, said plug being adapted to move from the seat by gravity and to be held in engagement therewith by pressures exterior to the tubing, means at the upper end of the plug for engagement with a fishing tool by which the plug may be returned to its seat, and means in spaced relation to said seat and beneath said screen to receive and support the plug when separated from its seat.

9. The combination with a well tubing having an inlet at its lower end, of means providing a downwardly facing valve seat at the interior of the tubing, a valve plug engaging said seat, said plug being held in engagement with the seat by pressures exterior to the tubing and when unseated moving by gravity to a point disposed below the current of fluid entering the inlet whereby said fluid will not reseat the plug.

10. In a well, the combination of a casing, a tubing within the casing and sealed to the casing at the upper end of the casing, a controllable connection between the casing and tubing and a closure valve for the lower end of the tubing maintained in engagement with the lower end of the tubing by casing pressures alone, said valve when unseated moving by gravity to a position from which it is unreseatable by fluids entering the tubing.

HERBERT C. OTIS.
